HEDDLE FRAME

Charles E. A. Lausberg, Haledon, N. J.

Application March 29, 1935, Serial No. 13,617

2 Claims. (Cl. 139—92)

In a known type of heddle frame for looms the frame proper, rectangular in form, has supported in its vertical portions or side bars and parallel with its horizontal portions or top and bottom rails a pair of flat heddle-supporting bars, or "heddle bars", on which the heddles are strung and which are frequently supported between their ends, to prevent their sagging under the heddle load and limit their motion in a direction through the frame, by hooks or hook-like devices directly or indirectly connected to the frame proper. When the load imposed on the frame is relatively light, as in the weaving with silk warps, the heddle bars are usually quite thin so that when they have to be disconnected for adding or removing heddles they may be readily bent and also twisted in order to clear them from or engage them with these hooks. But when the load imposed on the frame is heavy, as in the weaving with cotton or the like warps, the heddle bars are usually necessarily so thick that while they will respond to bending they do not readily respond to twisting, wherefore instead of using the aforesaid devices as their intermediate supports it has been proposed to use devices including latches or keepers movable thereon into and out of retaining relation with respect to the heddle-bars.

This invention relates to heddle frames having intermediate heddle-bar supporting devices of the latter class and it contemplates certain improvements whereby a sturdy and rigid support for each heddle bar is afforded, the operation of coupling and uncoupling such heddle bar is facilitated and the construction of the said device is rendered simple and inexpensive to manufacture.

In the drawing,

Fig. 1 is a face view of a heddle frame embodying the improved heddle-bar supporting device; Figs. 2 and 3 are fragmentary views on a larger scale of the heddle frame seen as in Fig. 1 and showing alternative forms of said device;

Fig. 2a is a section on line 2—2, Fig. 2;

Fig. 4 is a section on line 4—4, Fig. 2;

Fig. 5 is a fragmentary view on a still larger scale of what is shown in Fig. 4;

Fig. 6 is a section on line 6—6, Fig. 5, with the fixed member shown in elevation; and

Fig. 7 is a plan of the blank from which the sliding member is formed.

1 designates the side bars and 2 the top and bottom rails of the frame proper, and 3 designates the heddle bars carrying the heddles 4 and each penetrating the side bars and held in place under tension by the usual spring clips 1a affixed

to the side bars and having their ends engaged in holes in the heddle bars. In the present example a type of frame is shown in which the heddle bars are duplicated, a pair being arranged adjacent and parallel with each top and bottom rail. My device for supporting the heddle bars between their ends, which comprises a fixed member and a sliding member, is constructed as follows:

The fixed member includes a shank 5 which 10 may be secured to the rail in either of known ways, to wit, by threading one end thereof which, when passed through a hole in the rail, is clamped thereto by nuts 6 (Figs. 1, 2 and 4) or by threading it as a wood screw 7 which is driven 15 into the rail (Fig. 3). It has a lateral projection 8 to which one edge of the heddle bar, flanking the shank, will be presented and it may have in the same plane another such projection 9 to which the opposite edge of the heddle bar will 20 be presented, in which case the two projections form a crotch 10 to receive the heddle bar. If the heddle bars are in pairs, as above assumed, the projections 8 and 9 and crotch 10 will be duplicated at the opposite side of the shank. The 25 projections are thinner than the shank, being here formed as fins. Short of its free end the shank has opposed notches 12.

The sliding member or slide is formed from the elongated sheet metal blank shown in Fig. 7 whose body portion 13 has a central hole 14 and a pair of prongs 15 and a prolongation 16 between them projecting from each of its ends, there being a notch 17 left between the prolongation and each prong. The blank is rebent on 30 transverse lines and in one direction through its body portion and both sides of the hole to form the head 18 of the completed slide and then it is bent on other transverse lines and in the other direction through its body portion to form the 35 extremities of the completed (bifurcated) slide, each extremity shown including a web 19 adjoining the head and a portion 19a extending from such web (and which was in the blank the prolongation 16) appreciably narrower than the web. 40 From the head to its other terminal each extremity is formed part-cylindrical so as to be channeled at the inside and near its lower end it has an inside lug 20 adapted to engage the corresponding notch 12 of the shank and such end is inturned as at 21 to form an abutment. The projection formed by each lateral extremity of each web 19 has, as an incident of the notch 17, a hook 22 extending toward projection 8, where- 45 50 55

by such projections are coactive to hold a heddle-bar as shown in Fig. 4.

To assemble the members the fixed member is telescoped into the slide at the end of the latter having the abutments 21 and with the threaded end of the fixed member leading and its fins in the plane of the bifurcation-slit existing between the extremities of the slide, the assembly being complete when the other end of the fixed member passes said abutments, which thereafter serve to maintain such assembly until at least it is attached to the frame proper. The extremities of the slide hug the shank and due to some elasticity act to grip the same.

15 The device is attached to the corresponding rail so that the adjoining heddle bars, one at each side of the device, will be opposite the crotches 10. When the slide stands elevated on the fixed member in the position where its abutments 21 abut the free end of the latter each crotch 10 is open to permit entry of the corresponding heddle bar to or its removal from the same; the slide is releasably held in this position by engagement of the abutments 20 in 20 the notches 12. But when the slide is depressed, as shown, so that lugs 20 underlie said end of the fixed member the hooks 22 will lap the heddle bars if they have been made to occupy the crotches; the slide is releasably held in this 25 position (or against shifting out of heddle-bar locking position) by engagement of abutments 20 with said end of the fixed member, which they may however be made to clear by springing outward the somewhat elastic extremities of the 30 slide.

35

It is not new in these devices to provide a slide penetrated by the shank of the fixed member and one of which is provided with a heddle-bar retaining hook, as 22; but in the present 40 instance the slide is also bifurcated and its extremities receive the shank between them and are adapted to confine it to movement only lengthwise of the shank and to be made to coact with the shank in some way, such as is

herein indicated, to hold the slide releasably against movement, as when the heddle bar or bars are supposed to be locked in the device.

5 Since at least one extremity of the slide is channeled at the inside and receives the shank 5 in its channel such channel forms means to confine the shank and said extremities in parallel relation to each other.

Fig. 3 shows that instead of a nut, as 23, to hold the slide in locking position a spring 24 10 may be interposed between the rail and the slide.

Having thus fully described my invention what I claim is:

1. In a heddle frame, the combination of a 15 fixed member to be affixed to a rail of the frame and having a shank and a projection extending laterally from the shank, and a bifurcated slide having a lateral projection and being penetrated by and movable along the shank and having the 20 latter between and the first projection extending from between the extremities of its bifurcated portion, said extremities being closely related to and one of them having an inner channel receiving the shank and one projection having 25 a hook extending toward the other and adapted to lap a heddle bar interposed between the projections.

2. In a heddle frame, the combination of a 30 fixed member to be affixed to a rail of the frame and having a shank and a lateral projection, and a bifurcated slide having a lateral projection and being penetrated by and movable along the shank and having the latter between and the first projection extending from between the extremities of its bifurcated portion, one such projection having a hook extending toward the other and adapted to lap a heddle bar interposed between the projections and said extremities being elastic and gripping the shank and the shank and one extremity having a lug and notch interengageable to resist movement of the 35 slide along the shank.

CHARLES E. A. LAUSBERG.
